DESIGN FOR A TOOL HANDLE

George O. Leopold, Philadelphia, Pa., assignor to
North Bro's M'f'g Co., Philadelphia, Pa., a cor-
poration of Pennsylvania

Application March 1, 1940, Serial No. 90,617

Term of patent 7 years

To all whom it may concern:

Be it known, that I, George O. Leopold, a citizen
of the United States, residing in Philadelphia,
Philadelphia County, Pennsylvania, have invented
a new, original, and ornamental Design for a Tool
Handle, of which the following is a specification,
reference being had to the accompanying draw-
ing, forming part thereof, in which:

Figure 1 is a side view showing a tool handle
incorporating my new design, and

Fig. 2 is a section on the line 2—2, Fig. 1.

I claim:

The ornamental design for a tool handle, sub-
stantially as shown.

GEORGE O. LEOPOLD.
